UNITED STATES PATENT OFFICE.

JOHN J. MUELLER, JR., OF OTTAWA, ILLINOIS, ASSIGNOR TO SUPERIOR METAL CO., OF BETHLEHEM, PENNSYLVANIA, A CORPORATION OF PENNSYLVANIA.

POLISHING DEVICE.

Application filed October 23, 1922. Serial No. 596,283.

To all whom it may concern:

Be it known that I, JOHN J. MUELLER, Jr., a citizen of the United States, and a resident of Ottawa, in the county of La Salle 5 and State of Illinois, have invented a new and useful Improvement in Polishing Devices, of which the following is a full, clear, and exact description.

My invention relates to improvements in 10 polishing devices, and it consists in the combinations, constructions, and arrangements herein described and claimed.

An object of my invention is to provide 15 a device of the character described in which metal plates or strips may be cleaned and polished, in a continuous operation and by a single machine.

A further object of my invention is to 20 provide a device of the character described which is practically automatic in operation, and requires a minimum amount of care.

A further object of my invention is to 25 provide a device of the character described in which a continuous metal strip may be cleaned, and polished, and in which means is also provided for obviating the jamming 30 of the strip which might occur from slight irregularities which might be caused by warpage of the strip.

A further object of my invention is to 35 provide a device of the character described which is simple in operation, and which is thoroughly practical commercially.

Other objects and advantages will appear 40 in the following specification, and the novel features of the invention will be particularly pointed out in the appended claims.

My invention is illustrated in the accompanying drawings, forming part of this 45 application, in which—

Figure 1 is an enlarged sectional view of the polishing or buffing device,

Figure 2 is an end elevation, partly in section, of the mechanism illustrated in Figure 1.

My present invention consists in a polishing or buffing device that is fed manually and the construction thereof is more clearly shown in Figures 1 and 2. From 50 an inspection of Figure 1 it will be seen that the device 27 consists in a base portion 28 upon which a metal drum 29 is rotatably mounted by means of uprights 30 secured to the base 28. The drum 29 is formed of 55 a plurality of transverse slots 31 in its pe-

ripheral wall 32. One edge of the slot 31 is bent toward the center of the drum so that one of the plates, such as the plate 13, may be readily inserted with its end in the slot by moving the plate along the peripheral wall 32 of the drum in the direction of the arrow 33. It is in this manner that the plates 13 have their ends projected within the slots 31 prior to the clamping of the plates.

Means for clamping the plates 13 when their ends are projected within the slots 31 is provided in a cam 34, one end of which is in registration with each of the slots 31, respectively. An extension 35 of the cam 34 is arranged to extend inwardly toward the center of the drum and has a roller 36 rotatably mounted on its outer end. The cam 34 is pivotally mounted to the drum at 37 so that movement of the extension 35 toward the center of the drum will cause the cam to closely engage that portion of the plate 13 that is projected within the slots 31.

The plates 13 are admitted to the polishing or buffing device from the right hand side as viewed in Figure 1, and a stationary cam 38 is disposed within the drum 29 immediately adjacent the right hand peripheral wall of the drum. The cam 38 is a relatively short cam and serves to engage the roller 36 to cause the adjacent cam 34 to move away from the peripheral wall 29 of the drum so that the plate 13 may be readily projected into the slot 31. A second and relatively long stationary cam 39 is disposed 85 within the drum 29 and is adapted to engage the roller 36 to cause the roller to move toward the center of the drum immediately after it has been released from engagement with the cam 38. This movement of the roller 36 will cause the cam 34 to move 90 into close engagement with the plate 13 and hold the plate against movement as shown at 40 in Figure 1.

A buffer or polishing wheel 41 is disposed 100 immediately above the top peripheral wall of the drum 29 and serves to polish the exposed face of the plate 13. The cam 39 extends from the cam 38 to a point approximately opposite that point at which the plates were introduced in the slots 31. At 105 this point a third and relatively long stationary cam 42 is disposed within the drum 29. This cam 42, as reference to Figure 1 will show, is arranged to engage only every 110

other one of the rollers 36. This is because each alternate roller 36 is disposed in a certain vertical plane, while the remaining rollers are in another vertical plane. The 5 cams 38 and 39 are relatively broad and engage all of the rollers, while the cam 42 only engages every other roller.

In Figure 1 the cam 34 designated at X is in the act of being released from engagement 10 with the adjacent plate 13, since its roller 36 is one of those rollers which are arranged to engage with the cam 42. The plate 13 is therefore free to move away from the drum 29, which it does of its own weight 15 and by virtue of a chute 43 that is actuated by a cam wheel 44 of a cam 45 associated with the drum 29. The chute 43 is arranged to move toward the drum 29 at regular intervals and in synchronism with the engagement 20 of the rollers 36 with the cam 42.

An endless belt 46 is provided and is supported upon rollers 47 on the under side of the drum 29 so that the plates 13 will not bend downwardly and become engaged 25 with the base 28 or move out of engagement with the drum when the rollers 36 become released from contact with the cam 39.

Means for driving the polishing and grinding wheel 41 is provided in a pulley 30 wheel 50 on the shaft 51 upon which the grinding wheel 41 is disposed. A drive belt 52 extends downwardly over a pulley wheel 53 disposed on a shaft 54 upon which a gear 55 is carried which is in mesh with a gear 56 associated with the drum 29. A hand crank 57 is also provided for the shaft 57^a on which the drum 29 rotates.

From the foregoing description of the various parts of the device, the operation 40 thereof may be readily understood. With reference to Figure 1 it will be seen that the plates are first placed through a buffer or polisher 27. This device 27 which is clearly shown in Figures 1 and 2 is operated as follows. The plates 13 are manually grasped, one end thereof projected in the direction 45 of the arrow 33 into the adjacent slot 31 on the drum 29. At this time, the drum 29 and the grinding, polishing, or buffing wheel is 50 in operation, and the drum 29 is turning in a counterclockwise direction as viewed in Figure 1. The cam 34 adjacent the operator at this time will be moved away from the inner wall of the drum 29 and the plate 13 55 may be easily projected in the slot. The cam 34 will retain this position as long as its associate roller 36 is in contact with the stationary cam 38.

When the aforesaid roller 36 is moved 60 with the drum 29 upwardly for a short distance, it will engage with the stationary cam 39 and the cam 34 in the manner heretofore described, and will engage the plate 13 in close contact with the inner wall of 65 the drum 29. The plate 13 will then con-

tinue under the grinding, polishing or buffing wheel 41 and will make a complete revolution with the drum 29 back to its starting place. At this time, the cam 34, released 7 from engagement with the plate 13 by means of its contact with the stationary cam 38 and the plate 13, may be manually removed. A new plate will be substituted for the plate 13, and the plate 13 will be placed in the next adjacent slot 31. With reference to 75

Figure 1 it will be seen that every alternate cam 34 is provided with a roller 36 which lies in a different vertical plane from the remainder of the rollers. The cam 34, toward 80 which the plate 13 is now projected through the slot 31, is one of these alternate cams which has a roller that engages the stationary cam 38, the stationary cam 39, and also the stationary cam 42. It should be noted 85 at this point that the cam roller 34 previously described, and to which the plate 13 is first brought into contact, does not engage with the cam 42. When the plate 13 which has been reversed, that is, its outer 90 end has been made the inner end relative to the drum 29 which is the point X, its associate roller 36, which engages with the cam 42 and the cam 34, will be moved out of engagement with the drum 29 and the chute 43, thus permitting the plate 13 to be 95

scooped up by the shaft 14 that is at this time in close engagement with the drum. The chute 43 is adapted to be moved by means of the cam wheel 44 and the cam 45 on the drum 29 toward the drum at each alternate passing of the slots 31. In short, the device 27 is so constructed that the plates 13 may be inserted at the right hand of the device as viewed in Figure 1, and after passing under the grinding, polishing, or buffing wheel, will return to their starting point. The plate 13 may then be removed, reversed, and placed in the next successive slot 31 and at this time it will not be returned to its starting point, but be delivered from the machine at X or fall upon one pair of conveyor belts 10. 100

I claim:

1. A device of the character described comprising a polishing and grinding wheel, a rotatably mounted drum having its peripheral walls closely adjacent the peripheral edge of said grinding wheel, clamps associated with said drum for clamping metal plates or the like thereto, and means associated with said clamping members for releasing certain of said clamping members on a portion of the circumference of said drum as said drum is rotated, whereby certain of said plates may remain in said clamping members for a complete revolution of said drum and the remainder of said plates may remain in said clamping members for a complete revolution of said drum. 115 120

2. A device of the character described 125 130

comprising a polishing and grinding wheel, means for rotating the wheel, a drum rotatably mounted in close proximity with said grinding wheel, clamping members carried by said drum for clamping metal plates or the like thereto, means associated with said clamping members for releasing every second one of said clamping members dur-

ing one-half the revolution of said drum, whereby plates may be removed from the released clamping members at will during said one-half revolution of the drum, and other means for releasing all of said clamping members during a portion of the revolution of said drum.

JOHN J. MUELLER, JR.
